CLAIM

I claim the ornamental design for a bowl for a salad kit, as shown and described.

DESCRIPTION

FIG. 1 is a top perspective view of a bowl for a salad kit, showing my new design;

FIG. 2 is a bottom perspective view thereof;

FIG. 3 is a top plan view thereof;

FIG. 4 is a rear elevation view thereof;

FIG. 5 is a left elevation view thereof;

FIG. 6 is a right elevation view thereof;

FIG. 7 is a front elevation view thereof; and,

FIG. 8 is a bottom plan view thereof.
